CLAIM

The ornamental design for a cosmetic case, as shown and described.

DESCRIPTION

FIG. 1 is a perspective view of a cosmetic case showing my new design;

FIG. 2 is a top plan view of the cosmetic case;

FIG. 3 is a right side elevational view of the cosmetic case. The left side of the cosmetic case, not shown, is the same, the case being symmetrical in design.

FIG. 4 is a front elevational view of the cosmetic case.

FIG. 5 is a bottom plan view of the cosmetic case.

FIG. 6 is a rear elevational view of the cosmetic case.

FIG. 7 is a perspective view of the cosmetic case in an open position.
